CORNER BEAD

Donald E. Shaeffer, Manheim, Pa., assignor to Rimar
Manufacturing, Inc., Manheim, Pa.

Filed Feb. 25, 1970, Ser. No. 21,620

Term of patent 14 years

Int. Cl. D25—01

U.S. Cl. D13—1

FIG. 3

FIG. 4

FIG. 5

FIG. 1 is a front perspective view of a corner bead showing my new design.

FIG. 2 is an end elevational view thereof, the other end appearing exactly the same and opposite.

FIG. 3 is a rear elevational view thereof.

FIG. 4 is a front elevational view thereof.

FIG. 5 is a side elevational view thereof, the other side appearing exactly the same and opposite.

I claim:

The ornamental design of a corner bead, as shown and described.
